US00D641670S

(12) **United States Design Patent**
Thomas et al.

(10) **Patent No.:** US D641,670 S
(45) **Date of Patent:** ** Jul. 19, 2011

(54) **BRAKE PAD**

(75) Inventors: **John Larry Thomas**, Cedarburg, WI (US); **Christopher Sean Jones**, Bay View, WI (US)

(73) Assignee: **HB Performance Systems, Inc.**, Mequon, WI (US)

(**) Term: **14 Years**

(21) Appl. No.: **29/379,862**

(22) Filed: **Nov. 24, 2010**

(51) **LOC (9) Cl.** 12-16

(52) **U.S. Cl.** D12/180

(58) **Field of Classification Search** D12/180;
188/71.1, 73.3, 73.31-73.39, 72.2, 72.4,
188/73.41-73.46, 218 XL, 24.11, 24.12,

(57) **CLAIM**

An ornamental design for a brake pad, as shown and described.

DESCRIPTION

FIG. 1 is a front perspective view of an embodiment of a brake pad;

FIG. 2 is a front view thereof;

FIG. 3 is a rear view thereof;

FIG. 4 is a right side view thereof, with the left side view being a mirror image of the right side view;

FIG. 5 is a top view thereof; and,

FIG. 6 is a bottom view thereof.

The broken lines shown in the figures are for illustrative environmental purposes only and form no part of the claimed design.
